UNITED STATES PATENT OFFICE.

PHILIP F. CORBETT, OF BOSTON, MASSACHUSETTS.

CLAMP.

SPECIFICATION forming part of Letters Patent No. 292,207, dated January 22, 1884.

Application filed April 6, 1883. (No model.)

To all whom it may concern:

Be it known that I, PHILIP F. CORBETT, of Boston, in the county of Suffolk, State of Massachusetts, have invented a certain new and useful Improvement in Vises, of which the following is a description sufficiently full, clear, and exact to enable any person skilled in the art or science to which said invention appertains to make and use the same, reference being had to the accompanying drawings, forming a part of this specification, in which—

Figure 1 is an isometrical perspective view; Fig. 2, a vertical transverse section taken on line x ; Fig. 3, a like view taken on line z ; Fig. 4, a longitudinal sectional view of the head-stock, and Fig. 5 a vertical longitudinal section.

Like letters of reference indicate corresponding parts in the different figures of the drawings.

My invention relates to that class of vises which are employed for bench use by carpenters, cabinet-makers, and other wood-workers; and it consists in a novel construction and arrangement of the parts, as hereinafter more fully set forth and claimed, by which a simpler, cheaper, and more effective device of this character is produced than is now in ordinary use.

The nature and operation of the improvement will be readily understood by all conversant with such matters from the following explanation, its extreme simplicity rendering an elaborate description unnecessary.

In the drawings, A represents the body of the vise, B the head-stock, and C the tail-stock.

The body is provided on either side with a longitudinal groove, m , running its entire length, and on its top with an iron cap-plate, D, which is secured to the body by the screws x .

The head-stock consists of two downwardly-projecting flanges or side pieces, E, provided with horizontal studs d , disposed at their outer ends and working in the grooves m , and two cross-bars or uprights, G H, which connect the side pieces, E, above the body A. Mounted on the head-stock is a male screw, J, fitted to work in corresponding female screws in the uprights H and G, and provided with a guard, K, at its inner end, and a handle, L, at its outer end. Both the uprights being engaged by the screw, greater strength and directness

of movement are gained over a single engagement.

The tail-stock consists of two downwardly-projecting flanges or side pieces, M, connected by the cross-bar or upright N above the body A, the side pieces being provided at their outer ends with inwardly-projecting studs f , which work in the grooves m .

The plate D is provided with a series of vertical holes, g , and projecting downwardly from the bar N there is a stud or pin, l , adapted to enter the holes and secure the tail-stock in any desired position on the body A. A like pin (not shown) projects downwardly from the bar G of the head-stock and serves a like purpose.

In Fig. 5 a modification of my improvement is shown which is preferable for heavy work.

Projecting downwardly and backwardly from either end of the bar G, and next the side pieces, E, there is a tooth or dog, P, adapted to enter a corresponding mortise or slot, h , cut in the side of the body A, the slot inclining toward the tail-stock end of the vise, as shown. A like tooth or dog, i , projects downwardly from either end of the bar C, next the side pieces, M, adapted to engage in the series of mortises or slots Q, also formed in the side of the body A, but inclined toward the head-stock end of the vise, or in an opposite direction to the mortise h .

In the use of my improvement the body A is placed on any convenient bench or support, and its head-stock adjusted as shown, the pin in the lower part of the bar G being in one of the holes g and the studs d in the grooves m . The work to be glued or otherwise operated on is then placed across the top of the body or bed A, between the head and tail stocks, and the tail-stock moved up as closely as possible to the article to be clamped, the studs f being in the grooves m . The pin or stud l is then pushed downwardly into one of the holes g and the screw J turned in by the handle L, causing the work to be grasped between the guard K and tail-stock C in a manner which will be readily obvious without a more explicit description. The guard K is fitted loosely on the screw J, so that the screw may be turned without turning the guard and injuring the work. The tooth P, being inclined as shown, and hooking into the inclined mortise or slot

5 *h*, prevents the inner end of the head-stock from rising when a great strain is put on the screw *J* in doing heavy work. The tooth *i* also, in like manner, by hooking into the mortises *Q*, keeps the tail-stock in proper position.

10 It will be obvious that the inner ends of the head and tail stocks may be raised to enable the work to be inserted in the vise to better advantage, the stocks being respectively pivoted on the studs *d,f*.

15 The sides *E* and bars *G H* of the head-stock are cast integral or in one piece. The sides *M* and bar *N* of the tail-stock are also cast integral, and the body may be made of cast metal, or of wood and metal, as preferred.

20 It will be obvious that both the head and tail stocks may be readily removed from the body *A*, thereby adapting one set of stocks for use with several bodies, or, in other words, 25 preventing the necessity of having a body or bed-piece for each set of stocks.

Having thus explained my invention, what I claim is—

1. In a clamping-vise, a head-stock composed of downwardly-projecting cheeks or side pieces provided with inwardly-projecting

30 studs that slide in side grooves of the body, the uprights *G* and *H*, connecting the side pieces, a pin or dog adapted to enter a series of holes in the top plate of the body, and a horizontal screw extending through and engaging both uprights, in combination with the body provided with a longitudinal groove on each side, and with a tail-stock, substantially as described.

35 2. In a clamping-vise, a tail-stock composed of downwardly-projecting cheeks or side pieces provided with inwardly-projecting studs that slide in side grooves of the body, the cross-bar *X*, between the cheeks, and a pin adapted to enter a series of holes in the top plate of the body, in combination with the body provided with a longitudinal groove on each side, and a head-stock provided with uprights *G* and *H*, and a screw which engages both of said uprights, substantially as described.

PHILIP F. CORBETT.
